Primary Examiner—Raphael Barkai*Assistant Examiner*—Randall H Gholson(74) *Attorney, Agent, or Firm*—Klarquist Sparkman, LLP**CLAIM**

We claim the ornamental design for a combination carabiner and wrench device, as shown and described.

DESCRIPTION

FIG. 1 is a perspective view of a combination carabiner and wrench device, as viewed from the top and one side thereof, which includes a folding knife blade shown in the folded, or closed, position.

FIG. 2 is side elevation view of the right side of the device.

FIG. 3 is a side elevation view of the left side of the device.

FIG. 4 is a front elevation view of the device.

FIG. 5 is a rear elevation view of the device.

FIG. 6 is a bottom plan view of the device; and,

FIG. 7 is a top plan view of the device.
